BUCKLE FORMING MACHINE

Albert P. J. Voigt and Lawrence M. Still, Galveston, Tex., assignors to Galveston Buckle Company, a corporation

Application March 29, 1932, Serial No. 601,738

12 Claims. (Cl. 148—73)

The invention relates to a machine for making buckles which are particularly adapted for connecting the ties or bands used in confining cotton or other similar materials.

5 In forming bales, of material such as cotton, it is essential that the material be confined by suitable ties which can be quickly applied and which will permanently confine the material even when it has been compressed under heavy pressure. The invention will be particularly described in connection with buckles and ties used on cotton bales, but it is to be understood that the buckles may be used under any desired circumstances.

10 15 In the ginning of cotton the bales are formed at the gin in a low density pressure, that is, the bales are of considerable size and the cotton is not compressed under heavy pressure. When the bales are to be shipped any considerable distance, and particularly by steamship, it is desirable to have them compressed under a high pressure so that they will not occupy so great a volume. With this in mind the bales are placed in a high density press and reduced in size. In order to 20 hold the material in these high density bales it is necessary to have ties and buckles of great strength. With this in mind, the present invention has been conceived with a view of providing a machine which will produce a satisfactory 25 buckle to hold the ends of the bale ties on high density bales.

30 One of the objects of the invention is to provide a simple and economical machine which will form the buckles at a high rate and insure a 35 uniform product.

Another object of the invention is to provide 40 a buckle forming machine wherein all of the steps of forming the buckle are performed automatically and the machine will run at high speed without the services of an attendant.

Another object of the invention is to provide 45 a buckle-forming machine wherein what is termed a "safety buckle" is formed, as distinguished from the usual and well known type of C-buckle.

Another object of the invention is to provide 50 a machine wherein the wire from which the buckles are formed is fed into the machine, cut off, and bent into the desired form of buckle by a series of dies which periodically operate so that each die performs its intended function in connection with the forming of the buckle.

Another object of the invention is to provide 55 a buckle-forming machine wherein the parts are adjustable to accommodate different sizes of wire

to be used in forming buckles of different strength and wherein all of the parts are so positioned that the dies may move to properly support the wire while the same is being bent into the form of the buckle.

Other and further objects of the invention will be readily apparent when the following description is considered in connection with the accompanying drawings wherein

Fig. 1 is a side elevation of the machine showing the parts in position as the wire enters the machine just previous to being cut off in a length sufficient to form a buckle.

Fig. 2 is a top plan view of the machine seen in Fig. 1, with certain of the parts broken away which are above the general elevation of the machine.

Figs. 3 and 4 are sectional views taken on the line 3—3 and 4—4, respectively, of Fig. 2.

Fig. 5 is an elevation of the feeder wheel used to control the periodic movement of the wire into the machine.

Fig. 6 is an end view of the front of the machine looking toward the incoming wire.

Fig. 7 is a section taken on the line 7—7 of Fig. 2.

Figs. 8 to 11 inclusive are diagrammatic views illustrating the positioning of the dies and the wire during the steps of forming the buckle.

Figs. 12 and 13 are plan and edge views, respectively, of the completed buckle.

The general construction of the machine is best illustrated in Fig. 1 wherein the support 2, carries a frame or base 3 which serves as a foundation to which all of the remaining parts of the machine are attached. In order that the description will be best understood the various elements of the machine may be described in accordance with the sequence of operations in forming the buckles.

The feeder mechanism is best seen in Fig. 1 and comprises the guide rollers 9, a plurality of which are mounted on the frame so that the wire 11 will pass between them, with a view of straightening the wire. Two of these rollers are positioned on one side of the wire, while the third roller is positioned intermediate the two rollers and on the opposite side of the wire. There is also the feeder wheel 5, which is mounted upon a shaft 6 carried by the base 3. This feeder wheel has a geared portion 7 which meshes with a drive pinion 8, which may be driven by any suitable source of power such as an electric motor or drive belt.

This wheel is of a special construction as best

- seen in Fig. 5 in side elevation, or in top plan view in Fig. 2, and is provided adjacent one side with a groove 10, which is arranged to receive the wire 11, from which the buckles are formed.
- 5 Inasmuch as the wire is only to be fed into the machine periodically after each buckle is formed, and in view of the fact that an exact length is to be fed into the machine for each operation, a feeder flange 12 has been provided on the side 10 of the feeder wheel 5, and, as seen in Fig. 5, this feeder flange is raised slightly above the general circumference of the feeder wheel.

Fig. 7 shows a section which illustrates the groove 10, the feeder plate 12, and the roller 13, 15 which cooperates with the feeder wheel in controlling the movement of the wire into the machine. This roller is in the form of a pinion mounted upon a bracket 15, which is in turn carried by the yoke 16. This yoke is resiliently 20 mounted upon the uprights 17 and is normally urged downwardly by the springs 18. In this manner the roller 13 is maintained in engagement with the teeth of the feeder wheel 5, and the groove 20 of the roller 13 is maintained in 25 alignment with the groove 10 in the feeder wheel. The wire 11 will be fed into the machine due to its contact with these two wheels.

During the major portion of the time the wire is loosely positioned between the grooves 10 and 30 20 and there is insufficient friction to cause it to be fed forward. However, when the feeder plate 12 comes into engagement with the roller 13 additional friction will be created because of the fact that the feeder plate extends from the 35 circumference of the feeder wheel. The raising of the wire on the feeder plate will be resisted by the springs 18 so that additional friction will be caused, thus gripping the wire and feeding into the machine a length of wire equal to the length 40 of the feeder plate 12.

As soon as the feeder plate passes out of contact with the roller 13 the increased friction or grip on the wire will be released and inasmuch as the wire is being pulled from a carrier or reel 45 (not shown) it will only be moved into the machine so long as it is gripped between the feeder plate 12 and the roller 13.

As the wire moves into the machine it is intended that a predetermined length will be positioned so that the proper size of buckle will be formed. With this in mind a stop member 25 has been positioned in the machine, see Fig. 2. As soon as the wire has been passed into the machine so that it engages the stop 25 the next operation is to cut off the proper length of wire. To accomplish this cutting operation a blade 27 has been provided which carries a cutter 28. This cutter moves transversely of the wire 11 and severs the wire by passing adjacent the shoulder 60 29, so that a square cut on the end of the wire will be insured. The cutter 27 is reciprocated by means of the arm 30, which is driven by a cam 31. This cam 31 is caused to rotate by means of the beveled gears 32 and 33, which receive their power indirectly from the drive pinion 8, seen in Fig. 1.

The construction just described is best seen in Fig. 3 wherein the cam 31 is seen as being mounted on the shaft 32. The arm 30 is pivoted at 70 31 in the nature of a bell crank lever so that the upper end 34 thereof performs a lateral movement to cause reciprocation of the cutter 27. The cam 31 has an eccentric surface 35 thereon 75 which is designed so that the arm 30 will cause

reciprocation of the cutter blade 28 at the proper period during the operation of the machine.

A roller 36 is provided on the end of the arm 30 so that excessive friction will be eliminated. The position of the cutter 27 is adjustable by 5 means of the set screw 38. In order that the arm 30 will follow the eccentric surface 35, and in order that the cutter blade 28 will be removed from the path of the wire, a guard 39 has been attached to the face of the cam 31. The roller 10 36 when traveling on the cam surface 35 will pass between the forward end 40 of this guard and in this manner the cutter blade will be withdrawn.

It is to be understood that several of the operations in this machine are performed simultaneously but their description will be given in accordance with their sequence in forming the buckle. The next step after the wire has been cut is to grip the wire so that it may be bent 20 into the form of the buckle. To accomplish this, a buckle forming die or support 45 has been provided. This support is best seen in side elevation in Fig. 4 and comprises a die or core around which the wire is to be wrapped by the machine. 25 This die is best seen in end elevation in Fig. 8. The reciprocating movement of this die is accomplished by the arm 30, which is the same arm which operates the cutter 27. Their simultaneous operation is accomplished by the cross head 46 on 30 the arm 30, which carries the forming die 45. This forming die 45 moves beneath the wire, as seen in Fig. 8, at the same time that the end 48 of the wire is severed from the stock. It is to be noted, as best seen in Fig. 4, that the forward end 35 of the forming die 45 is indented as at 49 to conform to the inside contour of the buckle, as it is intended that the wire will be wrapped around this forming die during the operation.

The wrapping of the wire to form the buckle 40 is best illustrated diagrammatically in Fig. 9, as compared with Fig. 8, Fig. 9 being the next step in the process after the parts have assumed the position shown in Fig. 8.

In order to hold the piece of wire in proper position so that it may be wrapped around the forming die a stamp or vise member 50 is moved downward toward the wire to grip the wire and hold it firmly against the forming die 45. The movement of this vise 50 is accomplished by a 50 rocker arm 51, which is pivoted at 52 on the frame of the machine. The forward end of the arm 50' has a finger 53 which fits in the head 54 to cause raising and lowering of this head. The vise member 50 is adjustably positioned in the head and held in any desired position by means of the set screws 55 and 56. The spring 57 may be used to assist in raising the head and the vise 50 during its periodic operation. The rocker arm 50' is moved by means of a cam 59, which is also mounted on the shaft 32, and is provided with an eccentric face 60 and a guard arm 61, which corresponds to the cam 35 and the guard arm 39 on the cam 31. The cam 60 is of a different configuration, however, to provide for proper timing 65 of the movement of the vise member.

In order that the movement of the vise member 50 will be maintained in the same plane it passes through an opening 62 in the frame 63 of the machine.

When the wire has been firmly gripped between the forming die 45 and the vise 50, the next operation is to wrap the wire about the buckle die 45. To assist in maintaining the left end 65 of the wire, as viewed in Fig. 8, in proper position, and 75

to relieve the vise 50 of undue stress, an abutment 66 is provided on the portion 63 of the machine so that as the end 65 of the wire tends to turn upwardly it will come in engagement with this abutment 66. It is to be understood that the abutment 66 is fixed but is slightly above the elevation of the upper portion of the wire so that the wire may be moved into the position shown without striking the abutment.

10 The die for performing the wrapping of the wire is seen in section in Fig. 8 at 68, and is arranged to accomplish a rotative movement by being mounted upon a rotatable head 69, which is carried by the supporting structure 70. The die 68 is eccentrically mounted upon the head 69, and is formed with an eccentric face 71, which is arranged to contact the surface of the wire during the wrapping movement. As seen in Fig. 9, the wrapping die 68 traverses the path indicated 15 by the arrow so that it carries the end 48 of the wire 11 around three sides of the buckle forming die 45, forming one side 75 of the buckle, one end 76, and the opposite side 77. When the wrapping die 68 arrives at the position seen in Fig. 9 it 20 has then accomplished its function and it is quickly returned to the position shown in Fig. 8.

Movement of this wrapping die is accomplished 25 by a rack 80 and a pinion 81. The pinion is mounted in the support structure 70 and is 30 integrally fixed, or forms a part of the head 69. For purposes of simplicity the teeth on the rack 80 are inclined at an angle so that they engage 35 with the teeth on the pinion 81, which is positioned at the proper angle with respect to the wire 11 to accomplish the proper wrapping movement. As seen in Fig. 10, the end 48 of the wire is bent laterally to some extent during this wrapping movement so that it will pass the end 65 as it is wrapped about the buckle forming die 45.

40 It is for this purpose that the head 69 is inclined so that it does not rotate in the plane of the wire. Reciprocating movement of the rack 80 is accomplished by means of the arm 81', which is pivoted to a crank 82. This crank is in turn pivoted to 45 the base 3 at 83. Rocking movement of the crank 82 is accomplished by means of a roller 84, which travels in a groove 85 in a rotating cam 86. The groove 85 is so designed that it will accomplish 50 reciprocation of the rack 80 at the proper time interval so that the wrapping die 68 will carry the wire about the buckle forming die 45 directly after it has been clamped in the vise 50. Movement to the left of the rack 80, as viewed in 55 Fig. 2, causes the wrapping die 68 to move in a clockwise direction and the reverse movement reverses the rotation of the die, so that it will return to its inoperative position.

The next operation in forming the buckle, after 60 the end 48 has been wrapped to the position shown in Fig. 9, is to form the safety catch on the end 65. This operation is shown in Figs. 10 and 11 wherein the end 65 is bent laterally to form the safety hook 90. The end of the wire 65 must be supported in order to accomplish this bending 65 movement and the buckle must be given its final set by moving the end 48 into proper position with respect to the side 75 and the end 76. To accomplish this, a hook-forming die 91 has been provided. This die is shown in cross section in 70 Figs. 10 and 11 and is provided with a groove 92 on one side thereof to engage the end 48 of the wire 11. This die 91 moves vertically and is best seen in side elevation in Fig. 1. This die 91 can not be positioned during the wrapping operation 75 because it would interfere with the movement of

the wrapping die 68. For this purpose the hook-forming die is mounted to reciprocate in a vertical direction which reciprocation is caused by means of the arm 94, which is pivoted at 95 on the frame of the machine. Rocking movement of the arm 94 is caused by an eccentric face 96 on the cam 97. This cam receives its power from the shaft 32 by means of the beveled gears 98 and 99, the latter of which rotates the shaft 100 upon which the cam 97 is mounted.

10 The hook-forming die 91 is arranged to reciprocate through a suitable opening in the body 63 in a manner the same as the vise 50. It is to be understood that this forming die must be of sturdy construction as it must withstand the pressure of the dies which bend the wire into the formation of the safety hook, and it must maintain its final position so that the hook will have the proper set.

15 The die 91 is, therefore, arranged to move downwardly against the end 48 of the wire which has been wrapped so that the end 48 will move into the groove 92. The parts in Figs. 10 and 11 show the die in this position. As stated heretofore, the hook-forming die 91 is subjected to considerable 20 stress because the wire must be bent at a sharp angle. With this in mind the head 69 of the wrapping die 68 has been so formed that when the die 91 moves downwardly it will almost contact the head 69. Then, when the pressure is applied 25 in forming the hook, this hook-forming die 91 can move laterally a few thousandths of an inch so that the thrust against the die will be, in a major part, absorbed by the head 69, which has 30 by this time returned the wrapping die to its 35 normal position.

The surface 105 of the hook forming die is designed with such a configuration that it will form a more or less gradual curve in the wire at 106 and with a sharp bend at 107. The hook 90 is 40 so formed in order that the end 48 will move into the sharp bend 107. It has been found that a hook formed in this manner is of material advantage because the tension on the bale tie is applied to the side 75 and the side 77. This tension, when the pressure is released on the bale, 45 pulls the end 48 into the sharp bend 107. With the bend 107 positioned out of alignment with the end 108 the thrust on the side 77 is absorbed 50 by the bend 107, which is in direct alignment with the thrust. Other types of safety buckles have been devised heretofore wherein the sharp bend was in alignment with the end 108 of the buckle, but these buckles were found to be unsatisfactory 55 due to the fact that there was a moment arm available which tended to straighten out the hook of the buckle when it was applied to the bale tie.

For the purpose of forming the apex 107 out of alignment with the plane of the end 108, a pressure finger 110 has been provided, which is arranged for lateral movement transversely of the end 108. Fig. 10 shows this finger 110 moving into engagement to bend the end 65 of the wire about the hook forming die 91.

The pressure finger 110 is seen in plan view in 65 Fig. 2 in its retracted position. This finger is arranged for reciprocation by means of the bell crank lever 111, which is pivoted to the frame of the machine at 112. This lever is pivoted to the pressure finger carrier 113, at 114, and is provided with a roller 115 to engage an eccentric face 116 on the cam 117. A return cam or guard 70 119 is carried by the cam 117 so that the pressure finger 110 will be moved to retracted position after it has performed its function. The 75

cam 117 is mounted on the shaft 32 which has been previously described. The pressure finger 110 moves the end 65 of the wire into engagement with the hook forming die 91, which is in turn moved a very small distance to abut against the head 69 of the wrapping die. In this manner a rigid support is provided to withstand the thrust of the pressure finger 110 and provide for accurate positioning of the die to obtain a buckle 10 which will be bent in the exact manner desired.

When the end 65 has been moved to the position shown in Fig. 10 it is then necessary to complete the hook by bending the wire in the manner shown in Fig. 1. To accomplish this, a ram 120 has been positioned at the end of the machine and is driven by the bell crank lever 121. This lever is pivoted to the frame at 122 and is driven by the cam 123, which is fixed upon the shaft 100. A disc 124 carries the return or guard 15 cam 125 so that the ram 120 will be retracted after it has performed its function. An adjustment 126 is provided to arrange for accurate movement of the ram 120, which reciprocates through the guide member 127. The movement 20 of the ram 120 is so timed that it engages the end 65 of the wire immediately after the pressure finger 110 and completes the hook by bending the end of the wire around the hook forming die 91, as seen in Fig. 11. A support for the wire while 25 pressure is being applied to this ram 120 is accomplished by the hook forming die 91 engaging the end 48 of the wire, which during the entire operation has been wrapped around the buckle forming die 45. It is to be understood that at 30 this time the buckle is being completed and is still firmly held between the buckle forming die 45 and the vise 50. Proper set of the buckle to obtain the precise configuration desired is obtained at this time due to the timing of the parts, 35 because the upper end 108 of the buckle is firmly gripped between the vise 50 and the buckle forming die 45. The portion of the end 108 directly beyond that being gripped by the vise is against the underside of the abutment 66. The buckle 40 forming die 45 is inside of the buckle, as best seen in Fig. 9. The hook forming die 91 is inserted between the hook 90 and the inclined side 45 77 or end 48 of the wire and this hook forming die is so designed that it will complete the wrapping movement of the side 77 and give it the proper set or inclination, such as seen in Fig. 12.

The hook of the buckle is also wrapped around this hook forming die and the hook is given the proper set by the ram 120. It will be thus apparent that due to the timing of the parts the buckle will be properly formed, giving an exact set, and then released from the machine.

The release of the buckle is accomplished by the return movement of the ram 120, the pressure finger 110, and at this same instant the vise 50 is raised, as is the hook forming die 91. The buckle forming die 45 upon which the buckle now hangs is retracted so that the buckle drops by gravity out of the machine.

It is to be understood that all of the parts are adjustable for wear and for different diameters of wire so that buckles of different strength may be formed. The eccentric faces of the cams are so designed that the parts will have the proper timing and with machines in actual use it has been possible to deliver as high as one hundred twenty buckles per minute.

Having described the invention what is claimed is:

1. A bale tie buckle-forming machine includ-

ing means to feed the wire from which the buckle is to be formed, means to cut off a length of wire, a four-sided buckle-forming core arranged to be moved beneath the cut off wire, a vise to hold the wire against said core, a die arranged to be moved around the configuration of said buckle core to wrap one end of the wire about three sides of said buckle core, a hook forming die to set said wrapped end, and means to bend the other end of the wire laterally of the plane of the buckle to form a safety hook, and means to retract all of said dies and said core to release the buckle.

2. In a bale tie buckle forming machine, a wire support, a revolving die head, a die thereon to be revolved by said head around said support to bend the wire about three sides of said support, a hook forming die, and a plurality of means to form the buckle hook about said hook forming die, said hook forming die being movable to give 15 a set to the buckle and to be reenforced by said die head.

3. In a bale tie buckle forming machine wherein a length of wire is cut off in the machine to form the buckle, a vise and a buckle forming core, 20 means to move said vise down on the wire and said core beneath the wire at a point intermediate its ends so that the wire is firmly held, a wrapping die arranged to be moved about the configuration of said core to form the body of the buckle from one extending end of the wire, and means to thereafter form a safety hook from the other end of the wire while the wire is held.

4. In a bale tie safety buckle machine, a plurality of movable dies to bend the wire, one of said dies being movable about the configuration of one of said later mentioned dies to bend the wire about three sides thereof and a pair of movable dies around which the wire is to be bent by said first dies whereby the completed buckle is 40 dropped from the machine by gravity.

5. In a bale tie safety hook buckle machine, a plurality of movable dies to bend the wire, one of said dies being mounted on a revolving head and being movable about the configuration of one of said later mentioned dies to bend the wire about three sides thereof, and a pair of movable dies around which the wire is to be bent by said first dies, one of said last dies being shaped to the configuration of the buckle hook and positioned to abut one of said first movable dies to give the buckle the proper set.

6. A bale tie safety buckle machine of the character described including a plurality of dies, and means to move all the dies engaging the wire during the buckle forming operation whereby the buckle is released by the dies to fall by gravity from the machine, one of said dies being movable about the configuration of another of said dies to form at least three sides of the buckle.

7. In a wire bending machine, a core around which the wire is to be wrapped, a die arranged to be moved about the configuration of said core to bend the wire about three sides of said core, a vise to hold the wire against said core, a stationary abutment on the machine against which the free end of the wire will abut to relieve said vise of strain during the wrapping, and means to move said dies to release the buckle.

8. A bale tie buckle forming machine including 70 wire feeding means, a wire cutter, a reciprocating buckle forming die, a vise to clamp said wire in said machine against said forming die, a die arranged to be moved about the configuration of said forming die to bend one end of the wire 75

around said forming die in one operation, and a plurality of reciprocating dies adapted to engage the other end of said wire to form a hook thereon while the wire is held by said vise.

- 5 9. A wire bending machine including, in combination, a four sided die, means for positioning a length of wire against and across one side of said die, means to clamp the wire at such side with its ends freely extending away therefrom, means 10 spaced from said die and adapted to move in a circle around the remaining three sides of said die to engage one of said free ends and wrap it around said three sides, means engaging said other free end for bending the same into a hook 15 shape and means for actuating said several means.
10. A bale tie buckle forming machine including a buckle forming core of a configuration similar to the inside area of the buckle to be formed, means to feed a wire into the machine, means 20 to hold the wire against said core with its forward end in predetermined relation to said core, means moved about the configuration of said core to wrap the wire about three sides of said core in one continuous operation, and means to form a 25 hook on the wire on a portion adjacent that

which has been wrapped around the core in a plane to receive the wrapped end of the wire while said holding means retains said wire.

11. In a bale tie buckle forming machine, a buckle forming core over which the buckle wire 5 is positioned, an abutment beyond the said core, against which the forward end of the wire abuts, a die arranged to be moved about the configuration of said core to engage the wire and wrap it about three sides of said core in one continuous 10 operation, and means to clamp the wire against endwise movement during the forming operation by pressing the wire against said core.

12. In a bale tie buckle forming machine, means to hold the wire which forms the buckle, a core, 15 a wrapping die to wrap the wire around three sides of said core while it is held against said core by said first means, a die to move in between the ends of the wire when they are at right angles, a rounded surface on said die, and means to bend 20 one end of the wire about said surface so that a hook will be formed which is offset from the plane of the buckle to receive the other end of said wire.

ALBERT P. J. VOIGT.
LAWRENCE M. STILL. 25
